UNITED STATES PATENT OFFICE

120,216

DESIGN FOR A FLOWER BOX

Inez Craven, Chicago, Ill.

Application January 31, 1940, Serial No. 89,900

Term of patent 7 years

To all whom it may concern:

Be it known that I, Inez Craven, a citizen of the United States, residing at Chicago, in the county of Cook and State of Illinois, have invented a new, original, and ornamental Design for a Flower Box, of which the following is a specification, reference being had to the accompanying drawing, forming part thereof.

I claim:

The ornamental design for a flower box, as shown.

INEZ CRAVEN.
